UNITED STATES PATENT OFFICE.

JOHN LEWIS MILTON, OF LOUISVILLE, KENTUCKY.

INTERNAL-COMBUSTION-ENGINE EQUIPMENT.

Original application filed February 27, 1920, Serial No. 361,906. Divided and this application filed June 25, 1925. Serial No. 39,587.

An object of this invention is to equip a generator rotor with an improved impulse starter and completely enclose and thereby protect it from the dust and dirt encountered in the operation of the internal combustion engine. The impulse starter is designed to facilitate starting the engine by automatically and independently increasing the speed of the generator or magneto rotor upon slow or slight rotation of the engine shaft as in starting, thus affording substantially full electrical capacity of the ignition windings at very slow engine speed. When the engine is turned for starting, the generator rotor is held stationary while springs are strained, which are released at the proper time to accelerate the rotor at a high rate of speed for a part of a revolution. The initial spark or sparks for ignition having been obtained, the engine begins to fire regularly and when it attains the desired speed the impulse starter feature is automatically disengaged and the rotor is driven at direct or uniform engine speed according to the built in ratio of gears. A special feature of this impulse starter resides in the fact that the gear provided for driving the magneto is utilized for enclosing and assisting in operating the springs of the impulse starter. Both springs are used for impelling and stopping the rotor so as to relieve it of unnecessary and injurious pounding by sudden stopping.

A further object of my invention is to produce an ignition generator that can be economically and accurately installed directly on the gear case of an internal combustion engine and completely protect the impulse starter mechanism by said engine gear and oil not only these parts of the magneto by the engine's general circulating oil system but likewise the timing gears and bearing also the main magneto bearing.

Another object is to provide means for locking the rotor of the generator to the impulse starter by automatically connecting the two members together.

Referring to the drawings, Figure 1, represents a portion of an electric generator and impulse starter, shown partly in side elevation and partly in longitudinally section. Figure 2, is a view of the impulse starter taken along the line 8—8 of Figure 1. Figure 3, is a view of the impulse starter taken along the line 9—9 of Figure 1. Fig-

ure 4 is a fragmentary view similar to Figure 3 but showing the springs and the driver pin in normal or rest position; Figure 5 is a fragmentary sectional view of the same substantially through the center of Figure 6; Figure 6 is a perspective view of one of the parts of the device.

In the drawings I have shown a portion of the magneto frame 1 and the portion of the rotor shaft 6 which projects therefrom. Rotatably mounted on rotor shaft 6 is a helical gear 11 which is adapted to mesh with the timing gear of the engine, and which is provided on its side or face next to the magneto frame 1 with an annular groove 11^a. Projecting into and fixedly secured in suitable recessed portions of the gear are two diametrically opposite spring stops or abutments 40^b, best shown in Figures 5 and 6.

In the two halves or sections of the groove 11^a and located on opposite sides of the pair of stops or abutments 40^b are a pair of helical springs 40 into the ends of which are secured buttons 40^a for guiding and protecting the springs and for assuring good alignment with the stops or abutments 40^b and with driver pins 12^b—12^b which project into the groove 11^a from the yoke cage to be referred to presently.

Springs 40 are wound on an arbor and therefore produced in straight helical form and when equipped with the buttons 40^a and placed in the sections of the annular groove 11^a, will assume the position shown in Figure 3; i. e. the coils or convolutions of the springs located adjacent the center thereof will contact the outer wall of the groove 11^a and the coils or convolutions adjacent the buttons will be continuously held free or away from the walls of the gear both while at rest or in operation. This arrangement of parts adds greatly to the life of the springs and to the freedom of action of the parts.

Keyed to shaft 6 between the magneto frame 1 and gear 11 is an annular yoke cage 12 from the inner wall 12^a of which project the driver pins 12^b, these pins extending into groove 11^a between the buttons on the adjacent ends of the springs 40. The shape of the stops or abutments 40^b—40^b are such that the driver pins will at all times clear the same.

Slidably and loosely mounted in yoke cage 11^a

12 are two radially movable yokes 42 and 43 one having a lug 42^a and the other a lug 43^b, these lugs being oppositely disposed and being adapted when the yokes move 5 outwardly to project through the peripheral wall of the yoke cage. These yokes are so constructed and arranged that when the rotor of the generator is rotated at low speed as in starting, the weight of the yokes 10 will cause them to fall to the lowest position possible within the cage, this position being shown in Figure 2 for yoke 43, at which time lug 43^a is adapted to engage a fixed stop member 44 secured to the magneto frame 1 by screws 44^a or otherwise. When this engagement takes place the rotor and all parts fixed to it are held stationary 15 while the gear 11 continues to advance compressing springs 40—40 as indicated to an extent in Figure 3. While this is occurring trip pins 11^a and 11^b which project from the face of gear 11 into slots in the wall 12^a of the yoke cage progress toward cam faces 42^b and 43^b of the yokes 42 and 43. 20 After a predetermined relative movement between gear 11 and the rotor of the generator one of the trip pins engages the cam face of one of the yokes, in this instance the cam face 43^b, and lifts the associate yoke in this instance the yoke 43, until the projecting lug on the yoke clears stop 44. 25

The rotor and all parts of same are now rapidly propelled forward under the influence of the springs 40. As the springs 30 force their way back to normal position in the groove 11^a the momentum of the rotor and its parts now drive pins 12^b—12^b against the buttons attached to the other ends of the springs and force them from their seats 35 which are formed by the stops or abutments 40^b. In doing this the springs absorb the recoil without a sudden and harsh action, thereby increasing the life and usefulness 40 of the entire apparatus. As the speed of 45 the engine increases, centrifugal force acts on the yokes which are so weighted and proportioned that they rotate with their cage 12 without the lugs 42^a, 43^a, projecting. The drive is now direct with pins 12^b 12^b, being held in register with stops 40^b, 40^b, by 50 the springs 40, 40 and the buttons 40^a, 40^a.

Figure 3 shows the gear 11 advanced approximately 20 degrees and the spring 55 partially strained.

While I have shown my impulse starter mechanism directly mounted on the generator shaft, I do not limit myself to this application as others are quite possible. For instance I can attach it to the cam shaft or half time gear in which the speed of the rotor would be increased when the impulse starter springs are propelling. This would be of value when applied to a direct current generator. In Figure 1, I have

shown an automatic means for positively 65 locking the driving gear 11 and the driven members of the rotor together. Screw 50 is held in the position as shown by spring 51. As the speed of the generator is increased, the weight 52 progresses the screw 70 until the end 50^a meshes with the hole 12^a in yoke cage face 12^a, when positive locking is effected.

What I claim is:

1. In an impulse drive mechanism, the 75 combination of a rotary driven member, a rotary driving member adapted to have a limited turning movement in relation to the driven member, one of said members being formed with an annular channel, and resilient force-transmitting means disposed in said channel between abutments on said driving and driven members and comprising a coil spring structure and guide members seated in the end coils of said structure and engaging said abutments, said guide members and channel being greater 80 in diameter than the spring structure whereby the coils of the latter adjacent the guide members are held out of contact with the 85 channel walls.

2. In an impulse drive mechanism, the 95 combination of a rotary driven member, a rotary driving member adapted to have a limited turning movement in relation to the driven member, one of said members being formed with an annular channel, and resilient force-transmitting means disposed in said channel between abutments on said driving and driven members and comprising 100 a pair of coil spring structures and guide members seated in the end coils of said structures and engaging said abutments, said guide members and channel being greater 105 in diameter than the spring structures whereby the coils of the latter adjacent the guide members are held out of contact with the 110 channel walls.

3. In an impulse drive mechanism, the 115 combination of a rotary driven member, a rotary driving member adapted to have a limited turning movement in relation to the driven member, one of said members being formed with an annular channel, and resilient force-transmitting means disposed in said channel between abutments on said driving and driven members and comprising a pair of diametrically disposed coil 120 spring structures and guide members seated in the end coils of said structures and engaging said abutments, said guide members and channel being greater in diameter than the spring structure whereby the coils of the latter adjacent the guide members are held 125 out of contact with the channel walls.

In testimony whereof, I have hereunto set my hand this 23rd day of June, 1925.

JOHN LEWIS MILTON,
